CLAIM

The ornamental design for an electric bicycle, as shown and described.

DESCRIPTION

FIG. 1 is a front, right and top perspective view of an electric bicycle, showing my new design;

FIG. 2 is a rear, left and bottom perspective view thereof; FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged detail view of portion 9 encircled in FIG. 1;

FIG. 10 is an enlarged detail view of portion 10 encircled in FIG. 1;

FIG. 11 is an enlarged detail view of portion 11 encircled in FIG. 1;

FIG. 12 is an enlarged detail view of portion 12 encircled in FIG. 2; and,

FIG. 13 is an enlarged detail view of portion 13 encircled in FIG. 2.

In the drawings, the broken lines depict environmental subject matter only and form no part of the claimed design. The dot-dash broken lines depict the boundaries of the enlargements that form no part of the claimed design.

1 Claim, 13 Drawing Sheets
